Samuel Whitman
Potter Patent

The Schedule referred to in these Potter's Patent and making part of the same containing a description in the words of the said Samuel Whitman himself of his improvement in a Machine for the purpose of Making, Mortar and Tending Masons.

To all persons to whom these presents shall come, Samuel Whitman of Danville in the County of Vermillion and State of Illinois sends greeting. Be it known that the said Samuel Whitman have invented, ^{constructed} and made a new and useful Machine for the purpose of making Mortar and tending Masons called the Mortar Maker and Mason tender not known or used before. There can be as much labor performed by 3 men with this Machine as 10 men can do without it in the same length of time in the ordinary way. The Machine sifts the lime or washes it if necessary, mixes and prepares the mortar and carries the brick and mortar to the summit of the building to any height required. The foundation of the Machine is somewhat similar to that of the frame of a wagon with wheels to carry it about at pleasure. It is about 14 feet in length and 6 feet in breadth. The boxes wherein the lime and sand are sifted and mortar prepared are placed upon that part of the foundation which rests upon the hind wheels which I call the hind part of the machine. The machine goes by horse or by power. The horse walks upon an inclined band which is tightened and supported by rollers & in number which roll with the band nevertheless keeping their position and turning, upon their own axes. The band also goes round the main cog wheel on the main shaft and turns it which puts the whole in motion. Plate 1st fig 1st represents a brick building and the machine standing by it. The place of the mortar box, screen box, rollers, upright shaft, horse path or band, winding shaft, crane &c are plainly delineated in writing. B. L. & P. H. represent the cog wheels on the ends of

the main shaft described in plate 1 figure 2° the middle cog wheel being bid by the hand. Plate 1 fig 2° represents the foundation of the machine and the main shaft. The middle wheel is what I call the main cog wheel around which the band goes. This wheel is about 4 feet in diameter. The right hand cog wheel B.B. is that which turns the winding shaft represented in plate 1. fig 4. also in plate 1. fig 1. which winds the rope that carries up the brick and mortar. The cog wheel on the other end of the main shaft is that which moves the upright shaft represented in plate 1. fig. 1. This main cog wheel is under the rollers which the band rolls over and the band is kept in a triangular form the hypotenuse or longest side of which the horse walks upon. The band is composed of iron links fitted to mesh into the cogs on the main cog wheel and upon these links are fastened clats of wood from 4 to 6 inches wide one upon each link. This forms the path upon which the horse walks and occupies the middle part of the machine as you can see in Plate 1 fig. 1°. The band is from 2^{1/2} to 3 feet wide. The manner in which the band goes over the rollers and around the main cog wheel is represented in plate 1 fig 3° the ends of the rollers only being seen B.B. is the top part for the horse to go upon. This is a side view of the band. The band is also composed of 2 leather bands the one fastened to one end of the clats and the other to the other end of the clats one on each side of the iron chain and parallel with it and passing over the rollers in the same manner. This is done the better to steady, support and strength in the band. Plate 1 fig 4. represents the winding shaft which may in other words be called a spool which being slid off from a quay angle from A to B. will remain still whilst the other parts of the machine are in motion. B.B. represents the spool. A lever may be used in moving this spool. Plate 1 fig 5. represents the manner in which the winding shaft is suspended from the cog wheel P.P. which causes it to carry up the horse and geared into another cog wheel a little above it which turns at the contrary way.

way and lowered down the hoods. D. O. represents the cog wheel which is fixed stationary and is continually turned by the cog wheel P.H. that is on the fore end of the main shaft into which the winding shaft is geared to wind up the hoods. 2 levers are used for this one at each end of the winding shaft. B A D. represents the cog wheel on the winding shaft which being lifted up from B to A by the lever A.O. and geared into the cog wheel D. O. will be turned the other way and the hoods will be lowered. and the lever A.O. lowered from A to B. gears it again into the cog wheel P.H. The motion of the machine is regulated by means of a drum on the main shaft. Plate 1. fig. 2. which by its rubbing against a horn will impede its progress providing it shall go too fast. There is a large pole set in the ground upon which is hanged a crane to which the pulleys are fastened by which means the mortar and brick are carried to any height required. One man will be stationed upon the building to receive the hoods and place the contents where they are needed. The rope will also pass through a snatch block or pulley near the ground which is fastened to a short post. Plate 1 fig 1 represents the pulleys, hoods and hood frame and snatch block. Letter B. represents the snatch block. The upright shaft represented in plate 1 fig. 1. stands immediately between the band and the mortar and screen boxes. On the lower end of this upright shaft is a cog wheel about 1 foot and 6 in diameter which is carried by the cog wheel on the hind end of the main shaft meshing into it & turning this upright shaft. The crank on this shaft moves the rake in the mortar box more particularly represented in plate 2 fig 6 where the mortar box rake and crank and the manner in which the rake is pulled in and out as the crank revolves are to be seen. The cog wheels on the top of this upright shaft are those which turn the screen and likewise the shafts on each side of the upright shaft which revolve in the lime washers. The mortar box is the under one and the rake within moves by rolling friction. The

mortar box is about 1 foot and $\frac{1}{2}$ in depth 5 feet long and about 4 feet wide. The screener box is about 3 feet deep and directly over the mortar box. Plate 2 fig 7 represents the screener box and screener and rollers under the screener box. The screener outside is in form a cylinder revolves on its own axis. the lime and sand are put inside of it and are sifted and fall into the Mortar box. The breast cog wheel near the top of the upright shaft turns D.B. the cog wheel on the screener and this cog wheel turns B.H. one of the rollers and this roller has another cog wheel upon it that turns the other roller by the side of it. The two rollers are placed directly under the screener they mesh together and the lime falls in between them. These mesh and make fine all the lumps that may have escaped the screener. 2 inclined planes one on each side of the rollers nearly meet exactly between the rollers and draw the lime and sand into a very small compass.

They are nailed to 2 concaves one on each side of the rollers. The screener box is slid off leaving the mortar box open by means of an iron crank and 2 small cog wheels one on each side of the machine. The mortar box can then be tilted up and the contents emptied into another box upon the ground. This box has wheels to it to move it about as is most convenient. The wheels and axles may be taken off from this box and this box placed inside of the mortar box for the convenience of carrying. When it is necessary to wash the lime there are 2 boxes that are square one on one side of the upright shaft and the other on the other side crossways of the machine. The boxes are 1 foot and $\frac{1}{2}$ in depth. In each box is a shaft with rakes up on it 3 in number to stir up the lime water and a tunnel also to lead it into the mortar box. These shafts are turned by the cog wheel on the top of the upright shaft. Plate 2 fig. 8 represents the lime washers and the manner in which the cog wheel on this upright shaft meshes into the cog wheels on the shafts that revolve in the lime washers. It is expected that the weight of the

horse or ox upon the land will be of sufficient force to move all the machinery and raise the required quantity of bricks and mortar. But if the horse or ox should be too light or it be required to take a more than ordinary weight the power may be increased by drawing. The horse or ox can be made to draw by being geared to the posts of the machine immediately behind him. The ratio to take upon the lower ratchet upon the shafts that revolve in the line rollers is longer than the others and revolves in a channel through which the line rolls. The foundation of the lower judge on sides of this channel is supported by cross bars underneath it. The cross bar that connects the two levels together that are on each end of the winding shaft may be raised either by a windlass or lever and the winding shaft geared into the cog wheel that will turn it the contrary way. What I claim as my own invention and not previously known in the above described machine is the manner of putting together the several parts as above described on the principle therein laid down or in other words the combination and arrangement of the parts to that intent. In testifying that the above is a full and exact description of the mode of construction and operation of my machine as invented or discovered by me I have hereunto set my hand this twenty-seventh day of February eighteen hundred and thirty-five
